(57) **CLAIM**

The ornamental design for a virtual reality treadmill, as shown and described.

DESCRIPTION

FIG. 1 is a perspective view of a virtual reality treadmill showing my new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a perspective view thereof shown in use.

The broken lines depict portions of the virtual reality treadmill in which the design is embodied that form no part of the claimed design.
